(57) **CLAIM**

The ornamental design for a transformer housing, as shown and described.

DESCRIPTION

This application contains subject matter related to the following co-pending U.S. design patent application:

Application Ser. No. 29/572,447, filed herewith and entitled "Transformer Housing".

FIG. 1 is a front, top and left side perspective view of a transformer housing according to the design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is an enlarged partial view of frame 8 identified in FIG. 2; and,

FIG. 9 is a cross-sectional view taken along line 9-9 of FIG. 8.

1 Claim, 3 Drawing Sheets
